US0D1094280S

(12) **United States Design Patent** (10) **Patent No.:** **US D1,094,280 S**
(45) **Date of Patent:** **** Sep. 23, 2025**

(54) **PORTABLE POWER STATION WITH
INFLATOR**

(71) Applicant: **Shenzhen Fanttik Technology
Innovation Co., Ltd.**, Shenzhen (CN)

(72) Inventor: **Zhiqiang Liang**, Shenzhen (CN)

(73) Assignee: **Shenzhen Fanttik Technology
Innovation Co., Ltd.**

(**) Term: **15 Years**

(21) Appl. No.: **29/905,324**

(22) Filed: **Oct. 19, 2023**

Related U.S. Application Data

(63) Continuation-in-part of application No. 29/896,762, filed on Jul. 7, 2023, now Pat. No. Des. 1,084,994.

(57) **CLAIM**

The ornamental design for a portable power station with inflator as shown and described.

DESCRIPTION

FIG. 1 is a first perspective view of a portable power station with inflator showing the claimed design in accordance with the present disclosure;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the encircled portion of the portable power station with inflator labeled 9 in FIG. 1;

FIG. 10 is an enlarged view of the encircled portion of the portable power station with inflator labeled 10 in FIG. 3; and,

FIG. 11 is an enlarged view of the encircled portion of the portable power station with inflator labeled 11 in FIG. 5.

The broken lines in the Figures are for the purpose of illustrating portions of the article that form no part of the claimed design.

The dash-broken lines encircling portions of the claimed design that are illustrated in enlargements form no part of the claimed design.

1 Claim, 11 Drawing Sheets
